UNITED STATES PATENT OFFICE.

JAMES A. DAVIDSON, OF LOVELAND, COLORADO.

BLOWER-PIPE-RAISING DEVICE.

1,359,876.

Specification of Letters Patent. Patented Nov. 23, 1920.

Application filed May 16, 1919. Serial No. 297,678.

To all whom it may concern:

Be it known that I, JAMES A. DAVIDSON, a citizen of the United States, residing at Loveland, in the county of Larimer and State of Colorado, have invented certain new and useful Improvements in Blower-Pipe-Raising Devices; and I do hereby declare the following to be a full, clear, and exact description of the invention, such as will enable others skilled in the art to which it appertains to make and use the same.

This invention relates to raising devices, and more particularly to a device specially adapted for raising and supporting the blower tube or pipe of an ensilage cutting machine.

One of the main objects of the invention is to provide a device of the character stated of simple construction and operation which may be readily applied to an ensilage cutter of standard construction, and by means of which the blower tube or pipe of the cutter may be readily raised into position to discharge into a silo. A further object is to provide a device which may be quickly and easily adjusted to suit circumstances. Another object is to provide a device which will occupy a minimum of space and may be readily mounted upon the structure of the ensilage cutter. Further objects will appear from the detailed description.

In the drawings:

Figure 1 is a side view of a raising device constructed in accordance with my invention as applied.

Fig. 2 is a top plan view of the same.

Fig. 3 is a section taken substantially on line 3-3 of Fig. 2.

Fig. 4 is a detail of the lower portion of the raising device and the bracing and adjusting means therefor.

Fig. 5 is a detail of the locking pawl for the drum.

This device is adapted to be used in connection with an ensilage cutter designated generally by A of any suitable or standard construction, this cutter including the supporting frame B and a blower C all of well known construction. A flexible blowing pipe or tube D is adapted to be secured at its lower end to the discharge tube E of the blower, this pipe being provided at its upper end with a discharge elbow F for directing the ensilage into the silo.

In applying my raising device, I provide a supporting platform 1 which is rigidly se-

cured to frame B and extends in advance of the blower C. This platform supports an annular bearing plate 2 of I-cross section, the upper end of this plate fitting into an annular channel ring 3 disposed concentric with a socket member 4 secured to the upper face of platform 1, this socket member receiving a ball 5 depending from and rigidly secured to the lower end of the lifting device designated generally by 6. Ring 3 is provided on its upper face with three pairs of spaced ears 7 which receive heads at the lower ends of T-rods 8 positioned in alignment with similar rods 9 pivotally secured between ears 10 carried by the raising device 6, the adjacent ends of these rods being connected by a turnbuckle 11. By means of the rods 8 and 9 and the turnbuckles 11, the raising device can be readily adjusted so as to be tilted in any desired direction, and this device can also be readily turned or rotated upon ball 5 by turning the ring 3 and the parts associated therewith. This provides a universal adjustment for the raising device so that it may be readily moved into any desired position to hold the discharge elbow or hood of the blower pipe of the cutter in proper position to discharge into a silo.

The raising device 6 includes a plurality of telescoping members 12 of rectangular cross section and each provided in one side wall with a longitudinally extending slot 13, all of the slots of the members being in alignment, as illustrated. The innermost member 12 is provided with an inwardly projecting tab 14 through which is secured one end of a raising and lowering cable 15. This cable is led upwardly over a pulley 16 carried by inwardly projecting tabs 17 adjacent the upper end of the next to the innermost member 12, the pulley being then led downwardly about a pulley 18 carried by this member adjacent the lower end thereof, after which the cable is led upwardly over a pulley 19 carried by the next to the outermost member 12 adjacent the upper end thereof and downwardly about a pulley 20 carried by outwardly projecting tabs 21 of this member adjacent the lower end thereof, this cable being then passed upwardly over a pulley 22 carried by tabs 23 projecting outwardly from the outermost member adjacent the upper end thereof and wound onto a drum 24 rotatably supported by a suitable bracket 25 upon the outermost

member 12. A suitable crank 26 is connected to this drum for rotating the same in winding direction, and the drum is provided at its inner end with a ratchet wheel 27 engaged by a gravity pawl 28 mounted on the outermost member 12 for securing the drum against reverse rotation. The innermost member 12 is of greater length than the other members and is provided, at its upper end, with a supporting arm 29 adapted to be secured to the elbow or hood F of the pipe D. The blower pipe has been described as being flexible but it will be understood that this pipe can, if desired, be constructed of sheet metal sections, being provided at its upper end with a flexible discharge tube or section. In this case, the arm 29 is secured to the uppermost section, and the device may be utilized for raising the blow pipe as additional sections are applied thereto for increasing the length of the same. In either case, the operation, broadly stated, will be the same.

In practice, after the arm 29 has been attached to the blow pipe of the ensilage cutter in the manner described, by rotating drum 24 so as to wind the cable 15 thereon, the telescoping raising device 6 may be readily extended so as to elevate or raise the blow pipe, the raising device being readily adjustable so as to properly position the upper or discharge end of the blow pipe to direct the ensilage into the silo. By reversing this operation, the device may be readily lowered into inoperative or telescoped position, in which position it occupies but very little space and may, therefore, be readily carried upon the supporting structure or frame of the cutter. In practice, it may be desirable to make slight changes in details of construction and arrangement to accommodate the different makes of ensilage cutters in connection with which the device is used, and I intend to include all such variations, as fall within the scope of the appended claims, in this application in which a preferred form only of my invention is disclosed.

What I claim is:

50 1. A blower pipe raising device comprising a platform, a turn table mounted on said platform, a plurality of telescoping members adapted for rotation with said turn table, means for adjusting said members on an incline with respect to said turn table, one of said members being adapted

to be connected with the discharge pipe of the blower, and means for raising and lowering said members with respect to one another.

2. A blower pipe raising device comprising a platform, a socket mounted on said platform, a continuous track mounted on said platform, a turn table mounted for movement on said continuous track, a plurality of telescoping sections, one of said sections having a closed lower end a ball extended therefrom, said ball resting in said socket, means for connecting said section with said turn table and adjusting the incline of said section, a plurality of cable guiding members carried by said sections, a cable connected with one of said sections and extended around the cable guiding members of the various sections, and means mounted on the first mentioned section to wind said cable and raise the sections from within one another, one of said sections being adapted to be connected with a discharge pipe of a blower.

3. A blower pipe raising device comprising a platform, a turn table rotatable on said platform, a plurality of telescoping sections rotatably mounted on said platform, adjustable connecting and bracing rods secured at opposite ends to said turn table and to the outermost of said sections, said rods being adjustable to vary the angular incline of said sections, said sections having registering slots on one side and extended longitudinally, guiding pulleys mounted in said slot, a cable mounted within the innermost of said sections and extended around the pulleys of the various sections, a winding drum mounted rotatably on the outermost sections, said cable being connected with said drum and adapted to be wound thereon to force the sections upwardly from within one another, means to lock said drum against rotation in one direction and automatically, said means being adapted to be released to permit a return of the sections to position within one another, and means carried by one of said sections for connection with the discharge pipe of a blower.

In testimony whereof I affix my signature in presence of two witnesses.

JAMES A. DAVIDSON.
